AMPLIFIER

Klaas Posthumus, Eindhoven, Netherlands, assignor to Radio Corporation of America, a corporation of Delaware

Application August 23, 1929, Serial No. 387,828
In the Netherlands September 19, 1928

15 Claims. (Cl. 250—20)

The present invention relates to arrangements for amplifying electrical oscillations, and, more particularly, to methods of amplification without any appreciable distortion.

- 5 In an amplifier circuit arrangement, the total amplification present depends on the frequency supplied, because of the capacity of the discharge tubes used, and of the resonance curves of the oscillatory circuits present in the amplifier circuit 10 arrangement. As the discharge tubes have curved characteristics, the amplification also depends on the amplitude of the oscillations to be amplified. Due to these two causes, the curve shape of the voltage in the output circuit of an amplifier 15 circuit arrangement relative to the voltage on the input circuit shows deviations which, for example in testing curves and in the transmission and reception of sound vibrations, are undesirable.

The invention has for its main object an amplifying arrangement for obtaining a shape-true i. e., undistorted amplification or, if desired, an amplification obeying a definite law.

According to the invention, an x th-portion of the output voltage (in which x is small relative 25 to the degree of amplification of the amplifying circuit arrangement), is coupled back in counter-acting sense to the primary side of the amplifier circuit arrangement.

The novel features which I believe to be characteristic of my invention are set forth in particularity in the appended claims, the invention itself, however, as to both its organization and method of operation will best be understood by reference to the following description taken in 30 connection with the drawing in which I have indicated diagrammatically several circuit organizations whereby my invention may be carried into effect.

The invention will be described more fully with 40 reference to the accompanying drawing in which the Figures 1 and 2 diagrammatically represent, by way of example, an embodiment of the invention.

Fig. 1 represents a single tube amplifying circuit-arrangement comprising a discharge tube 1 and an impedance 5. The voltage V_1 , to be amplified, is supplied, for example, by a source 6 of alternating current. The voltage is applied to the grid of the amplifier tube 1 and is amplified by the 45 said tube 1 and by the impedance 5 in such a manner that the output voltage V_2 is equal to $m \cdot V_1$ if a fraction of the output voltage were not coupled back into the input circuit of the amplifier tube.

55 Now, the arrangement is such that the two

voltages in the input circuit are in opposition so that the voltage to be amplified is

$$V_1 - \frac{1}{x} \cdot V_2$$

in which

$$\frac{1}{x} \cdot V_2$$

indicates the fraction of the output voltage which 10 is fed back. The voltage in the output circuit becomes:

$$V_2 = m \cdot \left(V_1 - \frac{1}{x} \cdot V_2 \right)$$

or

$$V_2 = \frac{m \cdot V_1}{1 + \frac{m}{x}}$$

If, consequently, the possible amplification, m , of the total amplifier circuit arrangement is large with relation to x , the factor

$$\frac{m}{x}$$

will be much larger than 1, so that V_2 is equivalent to $x \cdot V_1$.

If x has a constant value, as indicated in the drawing, in which

$$x = \frac{R_1}{R_1 + R_2}$$

the voltage V_2 in the output circuit of the amplifier circuit arrangement will be independent of 35 the frequency both in phase and in amplitude, and of the amplitude of the voltage to be amplified owing to which consequently a shape-true amplification is obtained. If desired, the amplification may be dependent on the frequency in 40 phase as well, as in amplitude, by replacing the resistances R_1 or R_2 by an inductance or a capacity, or by both of them, while the amplification of the amplifier circuit arrangement may be made dependent on the amplitude of the voltages to be amplified by leading back a fraction of the voltage in the output circuit, for example, through a discharge tube, or another device whose characteristic is dependent on the amplitude.

Fig. 2 shows an embodiment in which there is 50 obtained a linear amplification of a direct voltage, or of slowly fluctuating voltages. As shown, such a voltage is applied between contacts 7 and 8, and is amplified with the aid of a high-frequency, or a medium-frequency carrier wave sup-

plied, for example by an oscillator 9. This is done by applying said wave and the direct voltage, to be amplified, to the input circuit of a discharge tube 12. A condenser 10, provided in the 5 input circuit of the tube 12, prevents a short-circuit of the direct voltage between the contacts 7 and 8 through an inductance 11. A battery 16 serves to apply the necessary grid bias to the grid of the tube 12 so that the latter will operate in the bent portion of its characteristic.

10 The oscillations, amplified and modulated, in the tube 12 are applied to the grid of a detector tube 15 through circuits 13 and 14 which are tuned to the frequency of the carrier oscillation.

15 In parallel with the output circuit of this detector is mounted a condenser 16', if desired connected in series with an inductance 17, for short-circuiting the high-frequency or medium-frequency component of the output energy of the 20 detector.

Between the direct voltage on the terminals of the resistance 18 in the output circuit of the detector 15, and the voltage between the contacts 25 7 and 8 there is, however, no linear relation.

25 According to the invention, this is obtained by coupling back to the primary side of the circuit arrangement a fraction of the voltage in the output circuit of the total amplifier circuit arrangement, as shown in Figure 2, by means of connecting lines 19 and 20.

30 Although only two modifications are shown, the invention can be applied to any known amplifier circuit arrangement both for multi-stage circuit arrangements, and for high- and low-frequency amplifier circuit arrangements with transformer, 35 resistance, and choke-coil amplification.

If, however, the feeding-back of the energy into the input circuit cannot be effected without the 40 production of spontaneous oscillations, it is necessary to provide in the amplifier circuit arrangement filters whereby pre-determined frequencies are removed.

45 While I have indicated and described several systems for carrying my invention into effect, it will be apparent to one skilled in the art that my invention is by no means limited to the particular organizations shown and described, but that many modifications in the circuit arrangements, as well as in the apparatus employed, may 50 be made without departing from the scope of my invention as set forth in the appended claims.

55 What I claim is:—

1. A method of operating an amplifier to obtain linear amplification of direct current voltages which consists in modulating a local high frequency carrier current with said direct current, amplifying the modulated carrier, detecting the amplified, modulated carrier, and reversely feeding back a fraction of the detected current 60 whose reciprocal is small relative to the degree of amplification of the amplifier to the input of the amplifier.

2. In a high frequency system, a tube provided with a tuned circuit in its anode circuit, a source of locally produced oscillations coupled to the input electrodes of said tube, a source of energy for modulating said oscillations coupled to said electrodes, a rectifier tube having a tuned circuit between its input electrodes, both said 65 tuned circuits being magnetically coupled and tuned to the same frequency, a resistor in the anode circuit of the rectifier, and a direct current connection between an input electrode of said first tube and a predetermined point of said resistor for impressing on said last named input

7 electrode potential variations due to the rectified modulated oscillations.

3. A method of operating an amplifier to obtain linear amplification of a fluctuating voltage which consists in impressing local high frequency carrier oscillations and said voltage on the amplifier whereby said carrier is modulated in accordance with the fluctuations, detecting the modulated carrier, and feeding back in a reverse sense a part of the detected output whose reciprocal is small relative to the degree of amplification of the amplifier to the amplifier input. 10

4. A method of operating an amplifier to obtain linear amplification of a fluctuating voltage which consists in impressing local high frequency 15 carrier oscillations and said voltage on the amplifier whereby said carrier is modulated in accordance with the fluctuations, detecting the modulated carrier, and reversely feeding back a part of the detected output voltage which is related 20 in a predetermined manner to the degree of amplification of the amplifier to the amplifier input.

5. An amplifier for fluctuating voltages comprising an amplifier tube, means for impressing said voltages on the tube input, means for impressing a local high frequency carrier current on the input, a detector tube coupled to the amplifier output, and means for reversely feeding back to the amplifier input a part of the detector output whose reciprocal is small relative to the 30 degree of amplification of the amplifier. 25

6. An electrical system comprising an amplifier provided with an input and output circuit, means for impressing on the input circuit an alternating current voltage, an impedance in said 35 output circuit, and means for impressing upon the input circuit, in phase opposition to the said voltage, a fraction of the voltage developed across said impedance whose reciprocal has a predetermined small relation to the amplification power 40 of said amplifier.

7. A method of operating an electron discharge tube amplifier to neutralize inherent distortion thereof consisting in impressing currents upon the amplifier, detecting the amplified currents, 45 and impressing a predetermined fraction of the detected currents which is small with respect to the amplification factor of the amplifier, upon the amplifier to neutralize said distortion, and maintaining said fraction constant in magnitude 50 to render the amplified currents independent of the amplitude of the first named currents.

8. A method of operating an electron discharge tube amplifier to neutralize inherent distortion thereof consisting in impressing currents upon the amplifier, detecting the amplified currents, and impressing a predetermined fraction of the detected currents which is small with respect to the amplification factor of the amplifier, upon the amplifier to neutralize said distortion, said 60 fraction being impressed upon the amplifier in phase opposition to the first named currents.

9. A method of operating an electron discharge tube amplifier to neutralize inherent distortion thereof consisting in impressing currents upon the amplifier, detecting the amplified currents, and impressing a predetermined fraction of the detected currents upon the amplifier to neutralize said distortion and maintaining the product of the amplification power of said amplifier and the said fraction substantially greater than unity. 65

10. A method of operating an electron discharge tube amplifier to neutralize inherent distortion thereof consisting in impressing currents upon the amplifier, detecting the amplified cur- 70 75

rents, and impressing a predetermined fraction of the detected currents upon the amplifier to neutralize said distortion and maintaining the magnitude of said fraction at such a value that 5 amplified currents are equal to the product of the reciprocal of the fraction and said first named currents.

11. A high frequency system comprising an amplifier tube, a source of high frequency energy 10 to be amplified coupled to the grid and cathode of said tube, a resonant network, tuned to the frequency of said energy, in the anode circuit of said tube, a succeeding tube, a resonant network, tuned to said frequency, connected between the 15 input electrodes of said second tube, said networks being coupled, means connected to the input electrodes of the second tube to operate the latter as a detector, a resistor in the anode circuit of said detector tube, and direct current connections between said resistor and the said grid and cathode of the amplifier tube for impressing on the latter a fraction of the potential variations due to the detected amplified high frequency energy which has a predetermined small relation 20 to the amplification factor of said amplifier.

12. A high frequency system comprising an amplifier tube, a source of high frequency energy to be amplified coupled to the grid and cathode of said tube, a source of modulation 30 energy coupled to said amplifier input electrodes, means for operating said amplifier as a modulator, a resonant network, tuned to the frequency of said energy, in the anode circuit of said tube, a succeeding tube, a resonant network, 35 tuned to said frequency, connected between the input electrodes of said second tube, said networks being coupled, means connected to the input electrodes of the second tube to operate the latter as a detector, a resistor in the anode circuit of said detector tube, and direct current connections between said resistor and the said grid and cathode of the amplifier tube for impressing on the latter potential variations due to the detected amplified high frequency energy. 40

13. A high frequency system comprising an amplifier tube, a source of high frequency en-

ergy to be amplified coupled to the grid and cathode of said tube, a resonant network, tuned to the frequency of said energy, in the anode circuit of said tube, a succeeding tube, a resonant network tuned to said frequency, connected between the input electrodes of said second tube, said networks being coupled, means connected to the input electrodes of the second tube to operate the latter as a detector, a resistor in the anode circuit of said detector tube, and adjustable direct current connections between said resistor and the said grid and cathode of the amplifier tube for impressing on the latter a fraction of the potential variations due to the detected amplified high frequency energy which is small compared to the degree of amplification of the amplifier. 15

14. In a high frequency system, a tube provided with a tuned circuit in its anode circuit, a source of locally produced oscillations coupled to the input electrodes of said tube, a source of energy for modulating said oscillations coupled to said electrodes, a detector tube having a tuned circuit between its input electrodes, both said tuned circuits being magnetically coupled and 25 tuned to the same frequency, a resistor in the anode circuit of the detector, and a direct current connection between the grid of said first tube and a predetermined point of said resistor for impressing on said last named grid potential 30 variations due to the detected modulated oscillations.

15. In a high frequency system, an electron discharge tube provided with a tuned circuit in its anode circuit, a source of locally produced oscillations electrically coupled to said tube, a source of energy for modulating said oscillations coupled to said tube, a rectifier tube having input electrodes coupled to said tuned circuit, an impedance in the space current path of the 35 rectifier tube, and direct current connections between the input electrodes of said first tube and a predetermined portion of the impedance for impressing on the last named electrodes potential variations due to the rectified modulated oscillations. 40

KLAAS POSTHUMUS.

DISCLAIMER

1,996,830.—*Klaas Posthumus*, Eindhoven, Netherlands. AMPLIFIER. Patent dated April 9, 1935. Disclaimer filed January 19, 1938, by the assignee, *Radio Corporation of America*.

Hereby enters this disclaimer to claim 6 in said specification and to the methods covered by claims 7, 8, 9, and 10 of said patent, except when each of the methods of said claims is limited to detection by means of an asymmetrical conducting device for producing desired frequency changes in current.
